UNITED STATES PATENT OFFICE

MARION M. HUSMAN, OF NEW YORK, N. Y.

CAP

Application filed July 17, 1929. Serial No. 379,013.

This invention relates to apparel and more particularly to a cap adapted to be worn when swimming or bathing although it may be worn at other times.

One object of the invention is to provide a cap formed from a flat sheet of material and which may be very easily applied to the head and secured in covering relation to the hair without disturbing the hair and causing it to become mussed.

Another object of the invention is to so form the sheet that the ears and hair at the sides of the head will be covered and portions of the sheet may be folded to form flaps adapted to be extended rearwardly about the head in overlying relation to the rear portion of the sheet and joined so as to securely hold the cap in place upon the head.

Another object of the invention is to provide the portions of the sheet forming the flaps with securing means firmly attached thereto and so secured to the sheet that danger of the sheet being torn when the fasteners are connected to each other will be eliminated.

The invention is illustrated in the accompanying drawing, wherein

Figure 1 is a perspective view looking towards the front and side and showing the cap in use.

Fig. 2 is a rear view showing the manner in which the flaps are joined at the back of the head.

Fig. 3 is a view of the sheet from which the cap is formed, and

Fig. 4 is a sectional view taken on the line 4-4 of Fig. 3.

This improved cap is formed from a sheet of material of such size that it may envelope the head, as shown in Figs. 1 and 2, with the rear portion of the sheet extending downwardly at the back of the neck. This sheet, which is indicated by the numeral 1, is normally flat and if the cap is to be used for swimming or bathing it will preferably be cut from sheet rubber, although rubberized fabric may be used. If the cap is to be used for general wear, it may be formed of any suitable knitted or woven fabric according

to the uses for which the cap is intended. This sheet has its side edges curved so that they converge rearwardly and merge into the rear edge of the sheet and at its front the sheet is cut to define portions 2 which extend forwardly. By this arrangement the front edge of the sheet will extend across the forehead when the cap is worn and the extended portions 2 will project forwardly a sufficient distance to entirely cover the ears and hair at the sides of the face. Therefore, all of the hair will be covered by the cap and protected. Reinforcing disks 3 which are preferably formed of rubberized fabric, although any other strong material found suitable may be used, are applied to the under surface of the sheet near its opposite sides. The sheet is crimped transversely through the reinforcing disks, as shown in Figs. 3 and 4, and the crimped portions are straddled by tabs 4 which are also formed of rubberized fabric or other suitable material and have enlarged ends. These tabs or strips are passed through the fastening members 5 and 6 and after their ends have been disposed at opposite sides of the crimped sheet they are secured by rivets or other suitable fasteners 7 which are passed through them and formed with heads so that the tabs will be firmly fixed in place. By this arrangement the fasteners will be firmly secured to the sheet near opposite sides thereof and the portions of the sheet to which they are secured will be greatly reinforced and danger of tearing the sheet when drawing the flaps about the head and uniting the fasteners will be eliminated.

When this cap is in use, it is held by grasping the tabs in each hand and placing upon the head with the front edge of the sheet extending across the forehead and the rear portion extending downwardly at the back of the head. The side portions of the sheet are folded to form flaps 8 which are drawn rearwardly so that they overlie the rear portion of the sheet and the fasteners united. Therefore, the forward portion of the sheet and the extensions 2 will be drawn tightly against the forehead and sides of the face in covering relation to the hair and ears

and the rear portion will be bound tightly into place. Since the cap is substantially a flat sheet throughout its entire area when removed it can be easily dried or washed if 5 necessary.

Having thus described the invention, I claim:

A cap comprising a sheet of material having portions at its front extending forwardly to cover a person's ears when the cap is worn, the sheet being adapted to be placed upon a person's head with its rear portion extending downwardly and its side portions folded to form flaps extended rearwardly 10 over the rear portion of the sheet, reinforcing disks applied against the under surface of said sheet adjacent opposite sides of the front portion thereof and the said portions of the sheet being crimped transversely 15 through the disks, tabs straddling the said crimped portions of the sheet and disks, fasteners passed through the tabs and disks to firmly secure the tabs, and companion securing elements carried by said tabs and adapted 20 through the disks, tabs straddling the said crimped portions of the sheet and disks, fasteners passed through the tabs and disks to firmly secure the tabs, and companion securing elements carried by said tabs and adapted 25 to be united to connect the flaps.

In testimony whereof I affix my signature.
MARION M. HUSMAN. [L. s.]
